T. V. BUCKWALTER,
APPARATUS FOR CHILLING BEARINGS.
APPLICATION FILED JAN. 23, 1919. RENEWED JUNE 5, 1920.

1,364,706.

Patented Jan. 4, 1921.

Inventor:

Tracy V. Buckwalter,

By Charles R. Butler

Attorney

UNITED STATES PATENT OFFICE.

TRACY V. BUCKWALTER, OF CANTON, OHIO.

APPARATUS FOR CHILLING BEARINGS.

1,364,706.

Specification of Letters Patent.

Patented Jan. 4, 1921.

Application filed January 23, 1919, Serial No. 272,635. Renewed June 5, 1920. Serial No. 386,918.

To all whom it may concern:

Be it known that I, TRACY V. BUCKWALTER, a citizen of the United States, residing at Canton, in the county of Stark and State of Ohio, have invented an Improved Apparatus for Chilling Bearings, of which the following is a specification.

This invention is designed to prevent the warping of articles, particularly anti-friction bearing cones or rings, due to chilling and hardening as by plunging the heated article in a cooling fluid, and a characteristic desideratum attained is the substantial reduction of the amount, cost and waste of grinding, otherwise involved.

The invention has the further advantages of attaining these objects simply, rapidly and efficiently, with consequent economy.

In the drawings, Figure 1 is a sectional elevation of apparatus comprised in the invention, Fig. 2 is a sectional view of details of the same including modifications in construction, and Fig. 3 is a sectional view taken on the line 3^x-3^x of Fig. 2.

The mechanism, as illustrated, is adapted for chilling the conical bearing rings 1 and preventing them from warping. It comprises a female die 2 provided with the inverted conical aperture and seat 2' adapted for engaging the exterior of the ring 1 in conforming relation, in combination with the inverted conical plug or male die 3 adapted to enter the ring in conforming relation and communicate continuous pressure thereto during shrinking, for the purpose of maintaining its shape.

As illustrated in Fig. 1, the plug or male die 3 is provided with the grooves 3' for the circulation of the cooling fluid therethrough in contact with the interior surface of the ring, and, as illustrated in Figs. 2 and 3, the female die 2 is provided with the grooves 2'' for the circulation of the cooling fluid therethrough in contact with the exterior surface of the ring.

The die 2 is adapted to rest upon a platen 4 which is carried by a rod 5 fixed to a piston 6, the latter acting in a cylinder 7 against the pressure of a fluid as air communicated thereto through the conduit 8.

The platen 4 is adapted to reciprocate in the cooling fluid receptacle 9 having an aperture 10 in the top thereof, with which the platen registers, and a rim 9' for preventing the overflow of the cooling fluid.

The platen 4 contains the passages 4' and

the recess 4'' communicating therewith, to permit the cooling fluid to flow freely therethrough and through the die mechanism holding the ring under pressure, as the 60 platen with the ring and die mechanism are forced downwardly into the cooling fluid against the resistance of the fluid in the cylinder 7 on the piston 6 and as these parts are elevated by the pressure of the fluid in 65 this cylinder.

The male die 3 is carried down by a rod 11, manually or otherwise, as by a piston 12 of larger diameter than the piston 6 and actuated by fluid pressure as air in a cylinder 13. The cylinder 13 contains a coiled spring 14 for retracting the piston 12 with the parts connected thereto when the air in the cylinder is released and is provided with a conduit 15 containing a three way valve 75 16 connecting it with the conduit 6, for admitting and releasing motive fluid which operates the pistons, the valve admitting fluid to both cylinders to squeeze and immerse the rings and releasing the pressure 80 in the cylinder 13 to effect the withdrawal of such rings.

The article to be treated is placed hot, at the hardening temperature, in the female die and pressed therein by the male die during quenching, the pressure following the article as its shrinks with the lowering of its temperature and preventing distortion as a result of the maintenance of the pressure until cooling and shrinking are completed.

Having described my invention, I claim:

1. The apparatus for chilling articles which comprises a receptacle having a top containing an aperture and a rim adapted 95 for preventing the overflow of liquid rising through said aperture, a platen adapted to reciprocate in said receptacle in registration with said aperture, a piston connected with said platen, a cylinder in which said piston acts, a die supported by said platen, a second die adapted to coact with said die first named in squeezing a heated article, a piston connected with said die second named, a cylinder in which said piston second named acts, and means for reciprocating said pistons to effect the immersion of said dies and articles.

2. The apparatus for chilling conical bearing rings which comprises a female die 110 having a conical seat, a conical male die, one of said dies provided with grooves, a

receptacle containing a cooling fluid, and means for pressing said dies together against a heated ring held between them and simultaneously immersing them in said cooling fluid to chill said ring.

3. The apparatus for chilling articles which comprises a pair of dies adapted for squeezing such articles, pistons connected with the respective dies, one of said pistons being of larger diameter than the other, cylinders in which the respective pistons are pressed in opposite directions, a spring for retracting the larger of said pistons, a re-

ceptacle for a cooling fluid, and means comprising conduits and valve mechanism for 15 simultaneously supplying fluid pressure to said cylinders, pressing said dies against an article held between them and translating said dies together to immerse said article, and alternately therewith releasing the pressure on the larger of said pistons while maintaining it on the smaller.

In testimony whereof I have hereunto set my name this 22nd day of January, 1919.

TRACY V. BUCKWALTER.
